SEVERABLE EGG CARTON

Andrew E. Bueschel, Chicago, Ill., assignor, by
mesne assignments, to Consolidated Carton,
Inc., Chicago, Ill., a corporation of Illinois

Application October 10, 1935, Serial No. 44,377

7 Claims. (Cl. 229—29)

This invention relates to cartons and particularly to cartons which may be readily separated into a plurality of disconnected units when found desirable to divide or separate the contents of the carton.

One object of the present invention is to provide a carton separable to form disconnected units having a plurality of compartments therein, and wherein the end compartments of the respective units adjacent the line of separation may be provided with proper closures and proper supporting means therefor to retain the contents in said compartments.

Another object of the invention is to provide a carton having a longitudinal partition and transverse partitions therein providing a plurality of compartments and separable transversely of its length to form a plurality of disconnected units, and to provide means for supporting a pair of partitions positioned, respectively, on the respective units to retain the contents in the compartments adjacent the line of separation.

Another object of the invention is to provide an arrangement whereby a plurality of carton blanks may be cut from a sheet of material in an economical manner to form transverse carton partitions of suitable dimensions, and without the loss of material in the formation of the blanks.

A further object of the invention is to provide retaining members for the respective carton units carried by the respective units of the carton structure.

A still further object of the invention is to improve an article of the character described in sundry details hereinafter referred to and particularly pointed out in the appended claims.

One embodiment of the present invention is shown for illustrative purposes in the accompanying drawings, in which:

Fig. 1 is a plan view of an open carton embodying features of the present invention and illustrating the means by which the carton may be separated into a pair of disconnected units;

Fig. 2 is an enlarged fragmentary longitudinal sectional elevation of the structure illustrated in Fig. 1, and taken substantially as indicated by the line 2—2 of Fig. 3;

Fig. 3 is an enlarged transverse elevational view of one end of a carton unit after the other unit has been disconnected therefrom, the view being taken substantially as indicated by the line 3—3 of Fig. 2, and illustrating features of the present invention associated therewith;

Fig. 4 is an enlarged fragmentary perspective

view of one end of a carton unit after the other unit has been disconnected therefrom;

Fig. 5 is a plan view on a smaller scale of a blank suitably formed and scored, from which the body portion of the carton is constructed;

Fig. 6 is an elevational view on a reduced scale of a longitudinal partition employed for providing a plurality of compartments within the body of the carton;

Fig. 7 is an enlarged fragmentary view of a portion of the blank shown in Fig. 5, illustrating more in detail certain of the structure embodied therein; and

Fig. 8 is an enlarged fragmentary view of the central portion of the longitudinal partition shown in Fig. 6, and illustrates more in detail certain of the structure embodied therein.

Referring to the drawings, the present embodiment of the invention illustrated therein is shown in conjunction with a carton suitable for containing eggs, or the like, indicated as a whole by the numeral 7, and comprising front and rear side walls 8 and 9, respectively, a cover member 10, bottom 11, vertically disposed transverse partition members 12, 12c and 12d, and a pair of central transverse partitions 12a and 12b, respectively, adjacent the central transverse portion of the carton. The transverse partitions 12 and 12c are operatively connected adjacent the upper edge portion of their respective ends to the front and rear walls 8 and 9, respectively, by means of flat web portions 13 and 14, while the central transverse partitions 12a and 12b are connected, respectively, to the front and rear walls 8 and 9 of the carton by flat web portions 12a' and 12b', respectively of slightly different form than the webs 13 and 14 related to the transverse partitions 12, 12c and 12d.

The illustrative embodiment also includes a centrally located one-piece longitudinal partition, indicated as a whole by the numeral 15, extending substantially the entire length of the carton 7 and having a plurality of recesses 16 formed in its lower edge portion for receiving the partitions 12, 12a, 12b, 12c and 12d, and having hook-like supporting portions 17 extending in a common direction and through elongated apertures 18 formed in an inner or false bottom 19. The latter is spaced from the bottom 11 and connected to the front and rear walls 8 and 9, respectively, of the carton by means of supporting strips 21 and 21a, respectively, (Figs. 1, 3, 4 and 5). The extending of the hook-like portions 17 in a common direction permits the use of a one-piece longitudinal partition such as 15, which is of mate-

rial advantage in assembling the partition 15 with the other portions of the carton structure.

To facilitate the separation or severance of the carton 7 transversely of its longitudinal dimensions to form a plurality of carton units 1a and 1b, the carton structure is provided with a weakened portion, shown, in the present instance, as a line of elongated perforations indicated, generally, by the numeral 22 formed in the cover 10, bottom 11, front and rear walls 7 and 8, respectively, and in the inner or false bottom 18 of the carton. The line of division is further defined by a weakened portion such, for example, as a line of elongated perforations, indicated generally by the numeral 23, formed in the central longitudinal partition 15 adjacent and between the recesses 16 in which the transverse partitions 12a and 12b are positioned, as clearly illustrated in Fig. 2, thereby forming a pair of retaining fingers 24 and 25 at opposite sides of the scoring 23 and adjacent the transverse partitions 12a and 12b, respectively.

It will be noted by reference to Figs. 1 and 7 that a perforation P of substantial length is provided between the webs 12a' and 12b' to permit easy separation of the webs 12a' and 12b' when the carton structure is severed into separate units such as 1a and 1b, and that the portions between the partitions 12a and 12b and their respective supporting webs 12a' and 12b' are weakened by cut scores 12a'' and 12b'', respectively, to facilitate bending down of the partitions 12a and 12b without distorting or rupturing the webs 12a' and 12b', and also that the partition 12b is somewhat shorter between the side walls 8 and 9 than the other partitions to facilitate bending down of the partition 12b without resistance by engagement of the ends thereof with the front and rear walls of the carton. A cut score 12x is provided also between the supporting strip 21a and the adjacent webs 12a' and 12b' to facilitate bending of the strip 21a in relation to the adjacent webs 12a' and 12b'.

By reference to Figs. 2 and 8, it will be noted that the line of perforations formed in the longitudinal partition 15, and indicated generally by the numeral 23, comprises a perforation 23a of substantial length, shorter perforations 23b and a perforation or notch 23c shown, in the present instance, as extending to the upper edge of the longitudinal partition 15 to facilitate severing of the partition transversely when the carton structure is severed into separate units 1a and 1b as above described.

It will be observed that by such an arrangement, the carton 7 may be readily separated along a line transversely of its length when found desirable to separate or divide the contents of a carton, as, for example, in selling or dispensing a half dozen eggs or the like, and that in such separation of the carton into a plurality of disconnected units, as indicated by the numerals 1a and 1b, the retaining fingers 24 and 25 of the respective separated portions of the longitudinal partition 15 will provide supports for the transverse partitions 12a and 12b, respectively, of the respective units to retain the contents of the compartments adjacent the line of separation against accidental displacement. Each of the disconnected carton units will be provided with a retaining finger for the central partitions 12a and 12b as clearly illustrated at 24 in the perspective view shown in Fig. 4.

It will be obvious by reference to Figs. 2 and 5 that the transverse partitions 12a and 12b are

formed in a common horizontal plane and extend in opposite directions at opposite sides of the line of scoring 23, and that the transverse partitions 12 and 12c and 12d formed in series at the respective opposite sides of the central partitions 12a and 12b are also formed in the same common horizontal plane and extend in the same direction as the transverse partition 12a, as clearly shown in Fig. 5, and are adapted to be swung downwardly in a like direction into spaced vertically disposed positions to form the transverse partitions shown in Figs. 1 and 2 of the drawings. The arrangement and formation of the partitions 12 and 12c in the manner above described is such as to permit the cutting of successive or adjacent blanks, as illustrated in Fig. 5, without waste or loss of material. It may be noted by reference to Fig. 5 that adjacent blanks may be formed side by side and ample material provided for the end partition 12c by extending it beyond the edge of an adjacent blank to form a recess in the adjacent blank as illustrated at A (Fig. 5) between the webs 13a and 14a at opposite ends of the partition 12d located at the opposite edge of the blank from the partition 12c.

Formed adjacent the front or free edge portion of the cover member 10 are a plurality of spaced locking tongues 26 extending in a common direction with respect to the cover and being adapted to cooperate with the web portions 13 of the partitions 12 and with the web portion 12b' of the partition 12b adjacent the front wall 7 for securing the cover member 10 in carton closing position.

If desired, the portions of the inner or false bottom 19, beneath each of the cells or compartments formed by the longitudinal and transverse partitions, may be cut through or perforated along arcuate lines 21, (Figs. 1 and 5) and the material inside the lines 21 may be cut through transversely along irregular lines 28, thereby providing tabs 29, one of the tabs being provided with a centrally located projection 31 and the other tab with side projections 32 extending beyond the free end of the projection 31 to provide an overlapping of the adjacent edges of the respective tabs. A portion of the false bottom material is left uncut and provided with a folding score 33 to form a weakened neck portion by which the tabs 29 are connected to the body of the false bottom 19. This arrangement provides tabs of a somewhat greater length than the distance between the false bottom 19 and the main bottom 11. It will be apparent that as eggs or similar articles are positioned on the tabs 29 of the false bottom 19, that the tabs will be forced downwardly out of the plane of the false bottom, thereby providing apertures for the reception of the eggs or other articles. The free ends of the projections 31 and 32 are moved into engagement with the main bottom portion 11 of the carton in a manner to assume an inclined position with respect thereto, thereby providing resilient supports for the eggs and protecting them against sudden or severe shocks to which they may be subjected in the handling of the carton.

Heretofore divisible boxes of this type have been proposed with a symmetrical structure with reference to the line of division, resulting in two 70 wings on the carton blank like wing 12c. These have been provided with two separate longitudinal partitions overlapping at the line of division. By the present structure a single and divisible partition is used for the 2 x 6 carton, and the 75

structure of the box is such as to permit easy insertion of the same. It is for this reason that all the down-foldable flaps extend in one direction, except cross-partition 12b, and this is made shorter as described to minimize the resistance it would otherwise offer because of its swinging reversely to the other flaps.

In setting up the box, the carton is opened from a flat form to a rectangular form in which the eight down-foldable flaps still lie in the cut panel which supplies them and their hinging tabs 13 and 14 or webs 12a' and 12b'. The single longitudinal partition is held in one hand and the finger at the right end of Fig. 6 is hooked into the slot in flap 12d, while the partition is at an acute angle with and above the length of the carton. The angle is then closed. In this action the projections 17 on the partition successively strike the flaps and turn them downwardly, the 20 projection 17 nearest the finger 25 at the line of division serving to fold down the odd flap 12b and also the adjacent regular flap in the same section. As the flaps near vertical position and before the projections 17 fully enter the holes 18 25 in the egg-rack 19, the projections are sufficiently effective to bend the flaps in the middle by a backward pull on the partition so that the projections may fully enter holes 18 and be locked on a slight forward motion of the partition.

It will be obvious from the foregoing description that the present invention provides a carton comprising but two elements, namely, the carton body and longitudinal partition 15, which may be quickly and readily assembled, and that the present invention also provides a carton capable of being separated transversely of its length into a plurality of disconnected units wherein suitable means are provided for the protection of the contents, and novel means carried by the respective units are provided for retaining the contents in the compartment adjacent the line of separation against accidental displacement.

Obviously, the present invention is not limited to the precise construction and arrangement shown and described as the same may be variously modified. Moreover, all the features of the invention need not be used conjointly as the same may be used to advantage in variously different combinations and sub-combinations.

What I claim as new and desire to secure by Letters Patent is:

1. A carton formed from a single sheet of material and having a main bottom, a false bottom having a plurality of apertures formed therein, longitudinal front and rear side walls, a cover member, supporting strips for supporting said false bottom in spaced relation to said main bottom, and a plurality of transverse partitions including a pair of central partitions integrally connected adjacent their end portions to said front wall and one of said supporting strips, a plurality of webs for connecting said partitions to said front wall and strip, the webs adjacent and between said central partitions extending inwardly a substantial distance from the side walls of the carton and being connected to said central partitions and to said last mentioned strip by cut-scored portions, said last mentioned webs adjacent the respective ends of said central partitions being separated by an elongated perforation formed in the material between said webs, and a longitudinal partition having a plurality of recesses formed in its lower edge adapted to receive said transverse partitions and having a plurality of hook-like supporting portions extend-

ing in a common direction and through said apertures to a position beneath said false bottom, said carton and longitudinal partition having lines of perforations formed therein and extending transversely thereof adjacent their central portions to facilitate separating the carton and longitudinal partition into a pair of disconnected units. 5

2. A transversely divisible carton of paper or the like having walls forming a cover, a bottom, 10 two longitudinal sides, and a panel extending between the two side walls and located above the bottom, said walls being weakened along a transverse line of division to permit readily dividing the carton into sections, said panel being cut to 15 provide down-foldable flaps which in folded-down position form transverse cell walls in the carton, there being a flap at each side of the line of division both arranged to swing toward each other to provide end walls for the divided sections, the remaining flaps of the carton being 20 formed to swing in the same direction as one of the two flaps at the line of division.

3. A transversely divisible carton of paper or the like having walls forming a cover, a bottom, 25 two longitudinal sides, and a panel extending between the two side walls and located above the bottom, said walls being weakened along a transverse line of division to permit readily dividing the carton into sections, said panel being 30 cut to provide down-foldable flaps which in folded-down position form transverse cell walls in the carton, there being a flap at each side of the line of division both arranged to swing toward each other to provide end walls for the divided 35 sections, the remaining flaps of the carton being formed to swing in the same direction as one of the two flaps at the line of division, and longitudinal dividing means intersecting flaps of said carton for dividing a space between adjacent flaps into cells. 40

4. A transversely divisible carton of paper or the like having walls forming a cover, a bottom, two longitudinal sides, and a panel extending between the two side walls and located above 45 the bottom, said walls being weakened along a transverse line of division to permit readily dividing the carton into sections, said panel being cut to provide down-foldable flaps which in folded-down position form transverse cell walls 50 in the carton, there being a flap at each side of the line of division both arranged to swing toward each other to provide end walls for the divided sections, the remaining flaps of the carton being formed to swing in the same direction 55 as one of the two flaps at the line of division, and a single longitudinal dividing partition intersecting flaps of said carton for dividing a space between adjacent flaps into cells, said partition crossing the line of division and being there 60 weakened to facilitate division of the partition with the walls of the carton.

5. A transversely divisible carton of paper or the like having walls forming a cover, a bottom, two longitudinal sides, an egg rack elevated from 65 the bottom, and a panel above the egg rack extending between the two side walls and located above the bottom, said walls being weakened along a transverse line of division to permit readily dividing the carton into sections, said panel 70 being cut to provide a plurality of down-foldable flaps which in folded-down position form transverse cell walls in the carton of approximately equal depth from top to bottom of the wall and which terminate closely adjacent the top level of 75

- the egg rack, the egg-rack being provided with cut portions to receive the ends of eggs lying between adjacent transverse cell walls, there being a flap at each side of the line of division both arranged to swing toward each other to provide end walls for the divided sections, the remaining flaps of the carton being formed to swing in the same direction as one of the two flaps at the line of division.
6. A transversely divisible carton of paper or the like having walls forming a cover, a bottom, two longitudinal sides, an egg rack elevated from the bottom, and a panel above the egg rack extending between the two side walls and located above the bottom, said walls being weakened along a transverse line of division to permit readily dividing the carton into sections, said panel being cut to provide a plurality of down-foldable flaps which in folded-down position form transverse cell walls in the carton of approximately equal depth from top to bottom of the wall and which terminate closely adjacent the top level of the egg rack, the egg rack being provided with cut portions to receive the ends of eggs lying between adjacent transverse cell walls, there being a flap at each side of the line of division both arranged to swing toward each other to provide end walls for the divided sections, the remaining flaps of the carton being formed to swing in the same direction as one of the two flaps at the line of division, a longitudinal dividing partition intersecting flaps of said carton for dividing a space between adjacent flaps into cells, said partition crossing the line of division and being there weakened to facilitate division of the partition with the walls of the carton, and spaced hooked projections carried by the partition, with each projection in contact with a flap and with hooks extending in the same direction for entering spaced holes in the egg rack, said partition being longitudinally movable in said holes to effect hooking engagement of the partition with the egg rack.
7. In a carton for eggs and the like having cross-wise cells therein formed between longitudinal sides of the carton, and a separate longitudinal partition dividing said cells into lengthwise rows, a panel cut to form a series of down-foldable flaps and connecting tabs in the plane of the panel which carry said flaps for folding each flap upon a hinging line of connection, said flaps serving to define cross-cells in said carton and being arranged to be intersected by said longitudinal partition, said flaps and tabs being arranged for all save one to swing in the same direction to parallel vertical positions, said one swinging in the opposite direction to a vertical position parallel with the others, said one flap being made shorter crosswise of the carton to give less resistance by minimizing drag on the longitudinal sides than the other flaps in folding all the flaps in one operation by using said separate longitudinal partition as a device to operate upon the series of flaps in folding them to vertical position.

ANDREW E. BUESCHEL
